a corporation of New Jersey

Application July 19, 1938, Serial No. 220,043

5 Claims. (Cl. 215—44)

This invention relates to closures for bottles, jars and various other types of receptacles and has for its object the provision of a closure cap of simple construction; one which is easily placed on and removed from its receptacle and which affords an efficient seal when in position.

The invention contemplates the provision of a closure cap preferably made of a single section of sheet metal and having a skirt portion formed with a rolled-up lower edge or bead adapted, when the cap is in position on the receptacle, to engage beneath lugs formed on the top portion of the receptacle. The rolled-up edge or bead formed on the skirt of the cap is so shaped as to enable it to be engaged by the lugs on the receptacle and thereby held firmly in seated position. Those portions of the bead which co-operate in the placement and maintenance of the cap in position on the receptacle are located on the inside of the cap and are not visible externally of the cap and since the skirt portion of said cap is not distorted or deformed, the exterior of the cap presents a smooth, unbroken appearance.

More particularly, the invention contemplates the provision of a cap formed with a downwardly extending skirt portion having its lower end so shaped that when said lower end is rolled upwardly within the body of the cap, it will provide a continuous, unbroken and undistorted bead encircling the lower end of the cap, the bead being of substantially the same cross-sectional shape throughout its entire length, but of varying diameter. I am aware that prior to this invention, it was common in this art to utilize a rolled-up bead on the lower end of a skirt portion of a cap for engaging with lugs provided on the neck of a bottle or other receptacle. However, in such prior uses, the bead so utilized was distorted or deformed at intervals to produce projecting lug elements adapted for engagement beneath the lugs on the receptacle. The production of these deformed or projecting parts on a bead requires additional manufacturing operations and increases cost and they sometimes tend to deform parts of the cap and provide an ill-fitting closure.

With my improved structure, mashing, compressing or deforming of the bead after its initial formation, is eliminated. It is merely necessary to roll up the bead, and the bead by its shape as initially rolled up and without further operations, will co-operate to produce a strong well-fitting closure.

55 In the accompanying drawing forming a part

hereof, Fig. 1 is a sectional view of the cap before the bead has been formed thereon; Fig. 2 is a sectional view through the unfinished cap of Fig. 1, the section being taken on the line 2—2 of Fig. 1, looking in the direction of the arrows; Fig. 3 is a sectional view through the completed cap, the view being taken on the line 3—3 of Fig. 5, looking in the direction of the arrows; Fig. 4 is a sectional view taken at right angles to that of Fig. 3, and on the line 4—4 of Fig. 5, looking in the direction of the arrows; Fig. 5 is a view of the underside of the cap; and Fig. 6 is a sectional view through the upper portion of a receptacle showing the cap in position thereon.

In the drawing, the reference numeral 1 indicates the top portion of a cap made in accordance with the invention. The cap is preferably formed by being pressed from a single section of sheet material which after being pressed, assumes the form shown in Figs. 1 and 2. The cap in the unfinished condition shown in Fig. 2 is thus provided at the marginal edges of the top 1 with a downwardly extending annular flange or skirt portion 2, the lower edge of which is undulated or curved as clearly shown in Figs. 1 and 2. For example, certain portions of the lower edge of the skirt 2 are downwardly curved as indicated at 3 in Fig. 1, and these downwardly curved portions of the lower edge of skirt 2 merge with upwardly curved portions 4. This irregularly shaped or undulated lower edge of the skirt 2 is rolled upwardly within the body of the cap and it results in the formation of a continuous bead 5 wholly located within the cap and concealed by the skirt thereon.

The irregularly formed or undulated lower edge on the skirt 2, which is curled or rolled upwardly to form the bead 5, results in the production of a bead of tapering formation or gradually reduced diameter at certain points in its length. For example, the downwardly curved portions 3 on the lower edge of skirt 2 produce the portions 6 of the bead of relatively large cross-sectional diameter, while the upwardly curved edge portions 4 on skirt 2 result in the production of the parts or areas 7 of relatively small cross-sectional diameter. The entire bead so formed, and clearly shown in Fig. 5, is thus for its entire length of the same cross-sectional shape, since it is not mashed or compressed or otherwise distorted, but it is of gradually reduced diameter at the several spaced areas 7 along its length.

A part of the receptacle adapted for reception 55

of the improved closure cap is shown at 8 in Fig. 6, said receptacle having a neck portion 9 formed with two properly spaced projecting rounded lugs 10, located diametrically opposite 5 one another on the neck of the receptacle. At the diametrically opposite points indicated at 1, the bead 5 is so reduced in diametrical size that it may pass by the lugs 10, or other suitably 10 formed projections on the receptacle neck. Then, as the cap is rotated, the portions of the bead of increasing diameter are forced under the lugs 10 with wedging action, due to the inclined surfaces 11 on the top edge portion of the bead, to securely and firmly seat the cap in position. The 15 bead is thus so shaped that the opening defined by it through which the top of the bottle projects is thus of smoothly oval formation. A gasket 12 of suitable material is of course provided in the inside of the cap in the conventional 20 manner.

It will be clear from the foregoing that by the simple operation of rolling up a bead on the lower edge of the skirt portion of the cap blank a bead of such shape is provided that it will efficiently 25 co-operate with lugs or other projections formed on the receptacle neck to seat the cap in position. Once the bead is rolled up or otherwise initially formed, no deformation, flattening, distortion or other operations common in the production of 30 sheet metal closure caps are necessary.

While I have shown the lower edge of the cap so curved or undulated to produce two diametrically located portions of the bead of minimum diameter, it will be apparent that by changing 35 the undulated shape of the lower edge of the skirt 2, the resultant bead formed by rolling up said edge may be provided with a greater number of portions in the bead of reduced diameter. Various other changes may be made in the structure 40 without departing from the spirit of the invention, as defined by the annexed claims.

What I claim is:

1. A closure cap having a dependent skirt portion formed with an integral rolled-up continuous 45 bead at its lower end, said bead being located interiorly of the cap and projecting inwardly

from the skirt and being concealed thereby, the bead being for its entire length of the same cross-sectional shape and having portions of gradually reduced cross-sectional diameter and of decreased interior projection from the skirt, said portions being located diametrically opposite one another on the skirt. 5

2. A closure cap having a dependent skirt portion formed with an integral rolled-up continuous bead extending without interruption or distortion 10 completely around the edge of the skirt, said bead projecting inwardly from and concealed by the skirt portion, portions of said bead at spaced points being of less cross-sectional diameter than other portions thereof and of less lateral projection toward the center of the cap than other portions, all portions of the bead being of like 15 cross-sectional shape.

3. A closure cap having a dependent skirt portion formed at its lower edge with a continuous, 20 undistorted integral rolled-up bead directed inwardly from the skirt, said bead having spaced areas of gradually reduced cross-sectional diameter whereby an opening defined by the bead is of oval formation, all portions of the bead being 25 of like cross-sectional shape.

4. A closure cap having a top and a dependent skirt portion, the lower edge of said skirt portion being continuously and uninterruptedly rolled up to form a continuous, undistorted 30 rounded bead extending completely around the edge of the skirt portion on the inside of the skirt portion, said bead being for its entire length of the same cross-sectional shape but being of gradually reduced cross-sectional diameter at several 35 spaced areas along its length.

5. A closure cap having a top and dependent skirt portion, a bead formed on the lower edge of said skirt portion on the inside thereof, said bead being undistorted for its entire length and 40 of the same cross-sectional shape and having portions of larger radii than other portions, said portions of larger radii being adapted to engage suitable projections on a container without interrupting the continuity of the bead. 45
